LOADING MACHINE

John L. Clarkson, Nashville, Ill.

Application October 26, 1935, Serial No. 46,842

14 Claims. (Cl. 198—8)

This invention applies to power-driven loading machines, such as are used for loading loose materials onto cars or trucks. While the invention is applicable to machines of the loading type generally, the machine selected for illustration in the accompanying drawings and which will be described in the following specification as an embodiment of the present invention, is designed as a coal loading machine for loading coal in mines.

In the usual working of a coal mine in accordance with a system in wide use in this country, the material is first separated from its bed in the mine by blasting, or shooting as it is called. To accomplish this operation the vein of coal is first undercut along the floor of the entry. For this purpose, a kerf is cut horizontally along the floor by a special cutting machine designed for that purpose. This kerf usually runs back six or eight feet from the face of the working, and is usually about six inches high. In some instances, a similar kerf is cut vertically through the middle of the vein. Shot holes are then drilled along the top and sides of the vein, into which blasting powder is loaded and in due course exploded. This operation has the effect of breaking the coal loose from the vein along the top and sides so that it settles down on the floor, the aforementioned horizontal kerf providing room for such settling. The blast also has the effect of cleaving or cracking the coal along its cleavage planes throughout that portion which is separated from the vein. In this condition, the coal is ready for loading on the mine cars.

The modern loading machine must be capable of attacking the coal in its shot-down condition, loosening or cutting apart the fragments thereof, and gathering up and loading on the cars the broken mass of loose material. Furthermore, such gathering and loading must be carried out at a high speed so as to cut down to a minimum the loading time per hour. In many instances the coal, upon being shot down, does not readily break up into separate fragments but must be broken up by the loading machine. This is accomplished by the present machine by digging its way underneath the pile of shot-down material. The digging and gathering head digs out the material from below the pile, gathers the same onto an elevating conveyor to be carried off, and keeps digging and working its way under the broken pile. It is, accordingly, equipped with digging devices adapted to dig away the pile of material in such a manner as to permit entry of the head of the machine underneath the pile.

One of the objects of this invention, therefore, is to provide a machine with novel digging devices adapted to clear a path underneath the pile for the entry of the head of the machine.

Another object of this invention is to provide means to prevent lodgment of material on the digging head in such a manner as to obstruct further entry of the head under the pile.

Another object is to provide novel means for adding to the digging and loading capacity of 10 the gathering head.

Further objects will appear from the following description taken in connection with the accompanying drawings, in which—

Figure 1 is a plan view of the front end of a 15 loading machine embodying this invention, showing the gathering head thereof;

Figure 2 is a side elevation of the same;

Figure 3 is a sectional view, taken on line 3—3 20 of Figure 1.

Figure 4 is a plan view similar to Figure 1, taken on line 4—4 of Figure 5, illustrating another embodiment of this invention.

Figure 5 is a side view similar to Figure 2, but partly in section on the line 5—5 of Figure 4. 25

Figure 6 is an enlarged detail of the front of the shoe seen in a view from the side similar to Figure 5.

Figure 7 is a detail section taken on line 7—7 30 of Figure 4.

The general structure of a loading machine of this character ordinarily comprises a traveling truck, which may be of the caterpillar tractor type or which may be arranged to run on tracks. This traveling truck usually carries the entire 35 structure. An elevating conveyor extends forwardly and downwardly from the traveling truck and functions to lift the material over the structure of the truck itself and deliver it to a second conveyor, usually carried at the rear of the truck. 40 This second conveyor ordinarily extends rearwardly from the truck and is adapted to deliver the material to the mine cars. The front end of the front or elevating conveyor is usually equipped with a gathering head whose function 45 it is to gather up the material and load it onto the elevating conveyor. For a detail description of a loader of this type, reference may be had to the patent to John L. Clarkson, No. 1,904,355, issued April 18, 1933. 50

In the accompanying drawings, only the forward end of the elevating conveyor is shown with its gathering head. The supporting structure of this elevating conveyor is indicated at 1 in the drawings, and the conveyor itself at 2. The con- 55

veyor 2 may be of any suitable type, that shown in the drawings consisting simply of two side chains connected by horizontally extending flights. The conveyor as a whole is arranged to 5 slide upwardly along a trough member 3 carried by the supporting structure 1.

Mounted on the forward end of the elevating conveyor is a gathering head 4. This is shown in the form of a flat plate or shoe adapted to 10 form a shovel at the front end of the elevating conveyor and mounted so as to extend down to the ground in front of the conveyor and extending upwardly and rearwardly so as to overlap the front end of the elevating conveyor. The 15 middle portion of this shoe or head is cut away so as to form a wide notch extending forwardly from the rear edge of the gathering head, the forward edge of this notch being indicated at 5. This notch is provided in order to expose the 20 conveyor 2 for delivery of the material thereto. It will be noted, from Figure 2, that the gathering head 4 is arranged at a steeper inclination than the elevating conveyor 2, the angular elevation of the shoe above the conveyor being indicated 25 at A. The purpose of this angular elevation will be explained hereinafter. The supporting structure 1 may be equipped with a shaft or axle 6, upon which may be removably mounted suitable road or track wheels, as indicated by the broken 30 line 7, for transporting the machine from place to place.

Suitably journaled on each side of the support 1 is a drive shaft 8, carrying at its upper end sprockets 9 and 10 and connected at its lower 35 end by bevel gears 11 and 12 with a transverse shaft 13 carrying a sprocket 14 driven by a chain 15 or other suitable drive from a main drive shaft 16. The main drive shaft 16 may itself be driven in any suitable manner from a motor, 40 usually mounted on the traveling truck. These driving connections are not shown in the drawing. The sprocket 9 is arranged to drive a gathering chain 17 equipped with suitable gathering arms or picks 18. At its lower end the chain 17 passes 45 around a sprocket 19 loosely carried by a stub shaft 20 supported in the structure 1. Gathering chains 17 are arranged in duplicate, one on each side of the conveyor 2, as seen in Figure 1. The arrangement is such that when driven in their 50 normal operation, the chains 17 travel in orbital paths on the head 4, as defined by the sprockets 9 and 19. The direction of movement is upwardly at the inner portion of their travel over the conveyor 2, as indicated by the arrows in Figure 1.

The chains 17, with their picks, which travel 55 in corresponding orbital paths over the head or shoe 4, provide means for gathering the material from the ground and progressing it over the lower end of the shoe and onto the conveyor 2. The 60 movement of the picks 18 is such that at the lower portion of their movement, where they pass around the lower sprocket 19, they extend beyond the end of the shoe 4 down to the ground and serve to pick up or loosen and cut away the 65 material in front of the forward edge of the shoe 4. The picks on opposite chains are interspaced with reference to each other so that they pass in front of the shoe alternately. They are arranged so that their paths cross beyond the end of the 70 shoe, and therefore they scrape the ground in front of the entire front edge of the shoe. This action serves not only to pickup all material from in front of the shoe, but also to cut away any lumps or high places which may protrude above 75 the normal level of the ground in front of the

shoe. This is important as it acts to continually cut down the floor of the mine in front of the machine to a constant level and thereby maintains the normal floor level for the mine.

Mounted above each of the gathering chains 5 17 is a cover plate 21. This plate serves to guide and protect the chains and prevent material from falling between them. The plate 21 may be supported by a longitudinal web 22 joined at its ends to transverse webs 23, the whole being preferably 10 welded together, and to the plates 21 and 4. These webs serve to stiffen the cover plate and to support it against the strain of material falling thereon.

In the operation of the gathering mechanism, 15 the picks 18, moving through their orbits as indicated in Figure 1, sweep the ground in front of the front edge of the shoe 4 and gather the material and pass it up onto the front portion of said shoe between the two chains. The picks 20 thus operate to progress the material over the shoe and deliver it over the edge 5 to the conveyor 2, which carries it upwardly over the traveling truck and delivers it to the second conveyor, which in turn delivers it to the mine cars as 25 already explained. The machine may be successfully operated in this manner and will be effective in loading coal or other loose material at a rapid rate. Where coal has been shot down, as already explained, the machine so equipped will 30 dig its way under the pile and carry out and load the loose coal. During such operation, the gather head often enters to a considerable distance underneath the pile, occasionally to such an extent that the entire gathering head is submerged. It 35 occasionally happens, however, that the shot material does not fall readily when loosened by the gathering mechanism, but remains suspended above the gathering head. It has been found also that loose materials sometimes accumulate on 40 the top of the cover plate 21 in a position where the picks 18 cannot reach them. Under such conditions, a pile of loose material lodged on top of the cover plate 21 may, when the head is worked under a pile of tight material, come into 45 engagement with the material suspended above the gathering head and thereby prevent further progress of the head under the pile.

In order to prevent this action, the present machine is equipped with a second pair of chains 24, 50 one of which is mounted to travel in an orbital path on top of each of the cover plates 21. These chains are also equipped with picks which travel in orbits similar to those of the picks 18. This upper chain is driven by a sprocket 10 on the 55 drive shaft 8 and passes at its lower end over an idler sprocket 25 also loosely mounted on the shaft 20. A second idler sprocket 26 guides the chain 24 inwardly to a point such that the material handled by this chain is delivered to the 60 conveyor 2. The sprocket 10 may be made of any desired size relative to the sprocket 9, and the relative speeds of the chains 24 and 17 will correspond to the relative sizes of these sprockets. These speeds may be given any desired value, but 65 it is usually desirable to have them run at about the same speed, or to make the upper chain 24 travel a little slower than the lower chain 17. It will be noted that, since the lower sprocket 25 of the clearing chain is relatively small in diameter, the picks 27 and 28 will pass around this sprocket at a relatively high speed. Accordingly, at this point these picks are actuated to deliver a sharp digging blow which is very effective in bringing down tight material.

The function of the chain 24 is two-fold. It is equipped with scraping or digging picks 27 and also with upstanding picks or horns 28. The picks 27 operate to sweep the loose material off the cover plate 21 and also to assist in digging new material from the working face. The upstanding picks 28 assist in these operations and also attack the material which may be suspended above the gathering head and operate to loosen or cut down that material so that it may be gathered and loaded by the machine. The chain 17 may also be equipped with upstanding horns or picks 29 which assist in the digging operation and also in cutting the suspended material above the gathering head. This arrangement enables the machine to cut its way into a pile of material, clearing all the material in front of it and even above it, and operating to gather this material onto the conveyor 2 and to load it onto the mine cars or other receptacles. The gathering head may thus work its way under tight coal, which refuses to fall but remains suspended above the machine. By attacking this suspended coal with the picks 28 and 29, said material is loosened and brought down upon the gathering head and is then gathered and loaded along with the rest of the material.

The usual conditions of operation in a coal mine are indicated in Figure 3, in which the dotted line 30 represents the working face of tight coal and the line 31 represents the lower surface operated on by the machine as it enters underneath the suspended material. The line 32 represents the floor line. As the operation proceeds, the picks 18, 29 and to some extent the picks 21, dig away the material in front of the shoe 4 and gather it onto the conveyor 2. As the head enters under the pile, the picks 28 and 29 come into play in operating upon the suspended material at the surface 31. Thus the digging operation takes place both in front of and above the gathering head simultaneously. The chain 24, with its picks, at the same time provides a clearing device to clear the accumulated material away from on top of the cover plate 21. A narrow top plate 33 may be provided to cover and protect the chain 24.

The conveyor 2 may be driven from the drive shaft 16 by sprockets 34 engaging the side chains of the conveyor. The cross shaft 13 may be made in two sections, as illustrated in Figure 1, the sections being connected by a flexible coupling 35 to allow for misalignment of the two sections of the shaft under flexure of the support 1, such as may occur when the head is unevenly loaded with material or obstructions are encountered in the operation thereof. The separate sections of the shaft 13 may, however, be entirely separated and individually driven by the chains 15. Suitable means, not shown in the drawing, are provided for raising and lowering the support 1 and for swinging the same laterally from side to side so as to provide for manipulating the gathering head, in order to reach materials in different positions with relation to the traveling truck.

In the operation of this machine, the traveling truck is operated to carry the machine to the desired point at which operations are to be carried out. The support 1 is manipulated on the traveling truck so as to present the gathering head 4 to the pile of material. The truck is then advanced so as to push the head against the pile of material. At the same time the shaft 16 is operated so as to drive the chains 17 and 24 and also the conveyor 2. Upon operation of the chains, the picks thereon become active in

cutting loose and gathering the material as already described. This material is passed on to the conveyor 2, which carries it away to be loaded on to the mine cars. It is desirable to drive the conveyor 2 at a somewhat higher speed than that of the chains 24 and 17. This accomplishes several advantageous results. It provides that all the material gathered will be promptly carried away and disposed of so as not to choke the gathering mechanism. At certain times in the operation of the machine, after the gathering head has cut its way under a pile of tight material, the material gives way and the entire mass falls upon the machine. Under such circumstances, a high speed of travel for the conveyor 2 is effective in carrying away the fallen material very rapidly, and this prevents the establishment of a deep pile of material upon the gathering head at the point where the picks 18 turn outwardly in their travel at the upper end of their orbit. If this outward turn were carried out under a deep pile of material, there would be danger of throwing most of this material off the machine, and this effect is prevented to a large extent by the extra speed of the conveyor 2 in carrying away the fallen material.

The increased elevation of the gathering head over that of the conveyor 2, as represented by the angle A, is also effective in clearing the picks before they turn outwardly to their return path. By virtue of this angle, the picks move in a path which rises with respect to the conveyor 2, and at their outward turn are spaced well above that conveyor so as to free the material carried thereby. This also prevents the effect of throwing this material off the machine.

It will be seen therefore that the arrangement is such that the machine not only gathers and loads the material which may be in front of it, but is capable of digging its way under a pile of tight material. The lodgment of loose material on top of the gathering chain is prevented by the operation of the clearing chain 24, so that any liability to obstructing the movement from this source is eliminated. Furthermore, means are provided for actually attacking overhanging material so as to bring that material down upon the gathering mechanism to be gathered and carried away for loading along with the rest of the material. Accordingly, practically every obstruction to the advance of the machine is eliminated by the action of this improved mechanism. It will also be noted that while the chain 24 is primarily a clearing device to prevent obstruction of the chain 17, it also has a gathering function of its own and co-operates with the conveyor 2 by supplying material thereto. While the orbit of the chain 17 is broad at its lower end so as to provide an ample sweep for the picks 18 in order to clear the front edge of the shovel, the corresponding portion of the orbit of the chain 24 is narrow, so as to avoid accumulation of any serious amount of material thereon.

In the embodiment of Figures 4 and 5, a modified arrangement of the clearing chain 24 is illustrated. In this case the clearing chain does not run the full length of the top plate 21, but extends only between the sprockets 25 and 26. This shortens the chain 24 and adds materially to its strength. Its clearing function is not impaired as it has been found that in most cases it is necessary to clear only the lower end of the plate 21.

In the embodiment of Figures 4 and 5, the clearing chain 24 is driven from the gathering

chain 17. The gathering chain driven by the shaft 8 functions itself to drive the sprocket 19 and thereby, through a common sleeve turning on the stub-shaft 20, the sprocket 25. The 5 sprocket 25 drives the chain 24. It will be noted that the direction of travel of chains 17 and 24, is the same so that the picks on both chains move upwardly at the inner portion of their orbit. The sprocket 26 is set near the inner edge of 10 the plate 21 so that the picks 27 on the chain 24, tend to carry the material inwardly and deliver it to the conveyor 2 in a manner similar to that of the picks 18 of the gathering chain 17.

It has been found that in some cases when the 15 gathering chain 17 becomes worn the picks 18 may have a tendency to sag. During the greater part of their travel these picks are supported upon the head 4. However, as they turn about the lower sprocket 19 they extend beyond the 20 end of the head 4 and at this point any tendency for a pick to sag, may cause it to interfere with the rail 40 on which the loading machine runs. Such interference between the pick and the rail while the pick is in motion, may tend to throw 25 the head of the machine to one side.

In order to overcome this defect, a curved supporting rail or ridge 41 is provided at the point where the gathering chain turns about the lower sprocket 19. This rail may be formed of 30 a simple strip or bar iron welded or otherwise secured to the head 4. In the arrangement shown in Figures 4 and 7 the rail 41 is welded to the head 4. The weld is carried out in such a manner as to provide an inner-bevel 42 extending along the inner-curve of the rail 41 to provide a bearing for the rear portion of the pick 18, as it passes around the lower sprocket 19. As the pick passes over this rail 41, its outer 35 end is elevated as shown in Figure 6, so as to clear the rail 40. The upper end of the rail 41, is provided with a rising approach as indicated at 43.

While this invention has been described as embodied in a unitary device, it will be understood 45 that individual features and sub-combinations thereof may be novel and useful of themselves without reference to the rest of the combination. It is understood that the employment of such individual features and sub-combinations 50 is contemplated by this invention and within the scope of the appended claims. It is further obvious that various changes may be made, within the scope of the appended claims, in the details of construction without departing from the 55 spirit of this invention; it is to be understood therefore, that this invention is not limited to the specific details shown and/or described.

Having thus described the invention, what is claimed is:

60 1. In a loading machine of the character described, an elevating conveyor at the front of the machine extending upwardly and rearwardly, a gathering head extending upwardly and rearwardly to overlap said conveyor and having a way therealong, a gathering chain moving on said head in a path extending upwardly and rearwardly and having picks adapted to gather the material and progress the same over said way and onto said conveyor, and a clearing chain 65 movable in a path extending upwardly and rearwardly above said gathering chain and having picks adapted to clear away material above said gathering chain.

2. In a loading machine of the character described having an elevating conveyor at the front

thereof, a gathering head overlapping said conveyor and having a way therealong, a gathering chain movable in an orbital path on said head and having picks adapted to gather the material and progress the same over said way onto said conveyor, and a clearing chain mounted to move in an orbital path above said gathering chain and having means to clear away the material above said gathering chain.

3. In a loading machine of the character described having an elevating conveyor at the front thereof, a gathering head overlapping said conveyor and having a way therealong, a gathering chain movable in an orbital path on said head and having picks adapted to gather the material and progress the same over said way onto said conveyor, a cover plate for said gathering chain, and a clearing chain mounted for orbital movement on said cover plate and having means thereon to remove loose material from said plate and to loosen tight material suspended above said head.

4. In a loading machine of the character described, an elevating conveyor at the front of the machine extending upwardly and rearwardly, a gathering head extending upwardly and rearwardly to overlap said conveyor and having a way therealong, a gathering chain moving on said head in a path extending upwardly and rearwardly and having picks adapted to gather the material and progress the same over said way and onto said conveyor, a cover plate for said gathering chain, and a clearing chain movable in a path extending upwardly and rearwardly above said gathering chain and having means to remove loose material from said plate and to loosen material suspended above said head.

5. In a loading machine of the character described, an elevating conveyor at the front of the machine extending upwardly and rearwardly, a gathering head extending upwardly and rearwardly to overlap said conveyor and having a way therealong, a gathering chain moving on said head in a path extending upwardly and rearwardly and having picks adapted to gather the material and progress the same over said way and onto said conveyor, a clearing chain movable in a path extending upwardly and rearwardly above said gathering chain and having picks adapted to clear away material above said gathering chain.

6. In a loading machine of the character described having an elevating conveyor at the front thereof, a gathering head overlapping said conveyor and having a way therealong, a pair of gathering chains having picks movable in paths leading inwardly toward each other beyond the end of said head, then upwardly over said way and extending along said conveyor to progress the material thereonto, said chains then moving outwardly away from each other to return paths, the paths of said chains at their outward movement being spaced above said conveyor sufficiently to free the material lumps thereon, and a clearing chain mounted above each of said gathering chains to move in an orbit substantially parallel therewith and having picks adapted to clear the material from above said gathering chain.

7. In a loading machine of the character described having an elevating conveyor at the front thereof, a gathering head overlapping said conveyor and having a way therealong, a pair of gathering chains having picks movable in

paths leading inwardly toward each other beyond the end of said head, then upwardly over said way and extending along said conveyor to progress the material thereonto, said chains then 5 moving outwardly away from each other to return paths, the paths of said chains at their outward movement being spaced above said conveyor sufficiently to free the material lumps thereon, a cover plate for each of said gathering 10 chains, and a clearing chain mounted for movement in an orbital path on said cover plate and having picks adapted to clear the material from said plate.

8. In a loading machine of the character described having an elevating conveyor at the 15 front thereof, a gathering head overlapping said conveyor and having a way therealong, a pair of gathering chains having picks movable in paths leading inwardly toward each other beyond the end of said head, then upwardly over 20 said way and extending along said conveyor to progress the material thereonto, said chains then moving outwardly away from each other to return paths, the paths of said chains at their outward movement being spaced above said conveyor 25 sufficiently to free the material lumps thereon, a cover plate for each of said gathering chains, and a clearing chain mounted for movement in an orbital path on said cover plate, and having 30 sweeping and cutting picks adapted to clear the material from said plate and to loosen the material thereabove.

9. In a loading machine of the character described, an elevating conveyor at the front of 35 the machine extending upwardly and rearwardly, a gathering head extending upwardly and rearwardly to overlap said conveyor and having a way therealong, gathering means moving on said head in a path extending upwardly and 40 rearwardly therealong, and a clearing chain movable in a path extending upwardly and rearwardly above said gathering means and having an upstanding pick adapted to loosen tight material suspended above said head.

45 10. In a loading machine of the character described, an elevating conveyor at the front of the machine extending upwardly and rearwardly, a gathering head extending upwardly and rearwardly to overlap said conveyor and having a way therealong, gathering means moving on said head in a path extending upwardly and rearwardly therealong, a clearing chain movable in 50 a path extending upwardly and rearwardly above said gathering means, and upstanding picks on

said gathering means and said chain adapted to attack material suspended above said head.

11. In a loading machine of the character described, an elevating conveyor at the front of the machine extending upwardly and rearwardly, a gathering head extending upwardly and rearwardly to overlap said conveyor and having a way therealong, a gathering chain moving on 5 said head in a path extending upwardly and rearwardly therealong, upper and lower sprockets 10 for said chain, and a clearing chain driven from said lower sprocket to move along and above said gathering chain.

12. In a loading machine of the character described, an elevating conveyor at the front of 15 the machine extending upwardly and rearwardly, a gathering head extending upwardly and rearwardly to overlap said conveyor, a gathering chain moving on said head to gather and move material onto said conveyor, and a clearing 20 chain moving above said gathering chain in a path deviating from that of said gathering chain adapted to clear away material above said gathering chain and move the same toward said conveyor.

25 13. In a loading machine of the character described, having an elevating conveyor at the front of the machine extending upwardly and rearwardly, a gathering head extending upwardly and rearwardly with respect to the front of said conveyor and having a way therealong, and gathering 30 chains moving on said head and having gathering arms rigidly connected thereto to gather the material and progress the same over said way onto said conveyor; means for preventing sagging of said arms where they extend beyond said head comprising a rail extending along the lower portion of the path of said arms adapted to elevate the tips thereof sufficiently to compensate for wear of their connections.

35 14. In a loading machine of the character described, an elevating conveyor at the front of the machine extending upwardly and rearwardly, a gathering head extending upwardly and rearwardly with respect to the front of said conveyor, gathering means moving on said head in an orbital path extending upwardly and rearwardly therealong, and clearing means movable 40 in a different orbital path of similar form to that of said gathering means but spaced thereabove and having a digging pick adapted to loosen material suspended above said head and moving in a path to clear said gathering means of material falling thereon.

JOHN L. CLARKSON. 55

CERTIFICATE OF CORRECTION.

Patent No. 2,141,148.

December 20, 1938.

JOHN L. CLARKSON.

It is hereby certified that error appears in the printed specification of the above numbered patent requiring correction as follows: Page 1, first column, line 42, for the word "hour" read car; and that the said Letters Patent should be read with this correction therein that the same may conform to the record of the case in the Patent Office.

Signed and sealed this 7th day of February, A. D. 1939.

Henry Van Arsdale.

(Seal)

Acting Commissioner of Patents.
